UNITED STATES PATENT OFFICE.

EDGAR V. WILLIAMS, OF RONDA, NORTH CAROLINA, ASSIGNOR TO WILLIAMS MILL MANUFACTURING COMPANY, OF RONDA, NORTH CAROLINA, A CORPORATION OF NORTH CAROLINA.

SIFTER.

1,051,295.

Specification of Letters Patent. Patented Jan. 21, 1913.

Application filed September 20, 1911. Serial No. 650,463.

To all whom it may concern:

Be it known that I, EDGAR V. WILLIAMS, a citizen of the United States, residing at Ronda, in the county of Wilkes and State 5 of North Carolina, have invented new and useful Improvements in Sifters, of which the following is a specification.

The present invention relates to improvements in sifters for separating meal from 10 bran.

In carrying out my invention it is my purpose to provide a sifter with supporting means which are adapted to impart both an oscillatory as well as a reciprocatory movement to the sifter, so that the contents of the sifter will be gently agitated and the meal quickly separated from the bran.

In devices of this class commonly employed, a reciprocatory movement only is 20 imparted to the sifter so that the meal is hurriedly conveyed over the screens and a portion of the meal is discharged out with the bran, causing a considerable loss in the quantity of the meal.

I successfully overcome the above objections by producing a four motion system device which embodies few parts, whereby the ground product is evenly distributed over the meshes of the sieve; the motion 25 imparted to the sieve being such as to cause all of the separate particles of the stock to contact with each other, as well as with the mesh of the sieve to separate every particle of meal from the bran.

It is also my purpose to provide a supporting means which may be easily and quickly attached to a sifting screen of any ordinary construction, and which will impart the desired motions to the screen.

For a full understanding of my improvement, reference is to be had to the accompanying drawings, in which—

Figure 1 is a central longitudinal sectional view of a screen provided with my improvement. Fig. 2 is a detail sectional view of the end supporting members. Fig. 3 is a front elevation of the screen and the attachment therefor. Fig. 4 is an enlarged sectional view taken upon the line 4—4 of 45 Fig. 3.

In the drawing, the numeral 1 designates a screen which is substantially semi-circular in cross section, and which is provided with closed ends. Secured upon one of the said 55 closed ends is a support 2, which comprises

an upper attaching portion 3 having an offset pivot member 4 which passes through an opening 6 in a substantially L-shaped bracket 5. The opposite or forward end of the screen has secured thereto a plate 7, 60 the latter being integrally formed with a longitudinally extending shaft 8 which is provided at its extremity with a rounded bearing 10. This bearing is peripherally formed with an inclined flange 11. 65

The numeral 12 designates the lower section of a journal box. The section 12 is provided with an inclined angular depression for the reception of the flange 11. The section 12 is provided also with an extending portion 13 which has its end provided with oppositely disposed arms 15 and 16, the said arms being connected with any suitable support. 70

The numeral 17 designates the upper section or top of the journal box, and which in turn is provided with an inclined angular depression that engages the flange 11 above that portion thereof received within the inclined depression of the journal 75 box section 12. The top 17 is sustained upon the section 12 through the medium of removable elements such as headed screws 18. 80

Integrally formed upon the shaft 8 is a curved arm 9, which has a rounded end that is received within a suitable bearing 19, the latter having connected thereto a pitman rod 20. The rod 20 is pivotally connected as at 21 with a collar 22. This 90 collar surrounds a flat wheel 23, which is eccentrically connected with a power shaft 24.

The operation of the device is as follows. The eccentric wheel 22 upon revolving will 95 cause the bearing 10 as well as its inclined annular flange 11 to revolve within its journal box 12, and thus impart an oscillatory as well as a reciprocatory movement. It will be noted that the particles of bran 100 carrying the meal within the sieve will be brought into contact with each other by this movement of the screen, the force of contact, however, being gentle so that the particles rubbing against each other will 105 by the process of attrition separate the bran from the meal without causing the breaking of the particles of the bran, and thus producing a high grade of meal.

It may be here stated that while the de- 110

vice has been described as a separator for meal from bran, it is evident that the said device could be equally employed in grading flour, if desired.

Having thus fully described the said invention, what I claim is:—

In a device for the purpose set forth, the combination with a screen having closed ends and a pivoted bearing for one of the ends, of a shaft secured to the opposite end of the screen, said shaft having its extremity enlarged to provide a rounded bearing, the said bearing being peripherally formed with an inclined flange, a journal box for the bearing and flange, the said box including a top, and both the top and box

being formed with an inclined annular depression for the reception of the flange, the axle being integrally formed with an outwardly curved arm, a pitman rod connected 20 with the arm, a collar for the pitman and a shaft provided with an eccentrically connected wheel which engages with the collar, all substantially as and for the purpose set forth. 25

In testimony whereof I affix my signature in presence of two witnesses.

EDGAR V. WILLIAMS.
